UNITED STATES PATENT OFFICE.

DAVID D. NOLLEY AND ROBERT L. WYATT, OF WILSON, NORTH CAROLINA.

CURTAIN-HOLDER.

SPECIFICATION forming part of Letters Patent No. 399,773, dated March 19, 1889.

Application filed June 2, 1888. Serial No. 275,893. (No model.)

To all whom it may concern:

Be it known that we, DAVID D. NOLLEY and ROBERT L. WYATT, of Wilson, in the county of Wilson and State of North Carolina, have 5 invented new and Improved Curtain-Holder, of which the following is a full, clear, and exact description.

The object of the invention is to provide a new and improved device for conveniently 10 lifting the lower end of the curtain to fold it to one side of the window, and for holding the curtain in place when in a folded or closed position.

The invention consists of an arm pivoted 15 on the window-frame, and provided at its free end with a clamp engaging the curtain.

My invention is an improvement in the class of curtain-holders consisting of a hook pivoted on the window-frame and adapted 20 for holding the curtain drawn back more or less.

The novel features of construction are as hereinafter described and claimed.

Reference is to be had to the accompanying 25 drawings, forming a part of this specification, in which similar letters of reference indicate corresponding parts in all the figures.

Figure 1 is a front view of the improvement as applied, showing one curtain in a 30 folded position and the other in a closed position. Fig. 2 is a vertical cross-section of the same on the lines $x x$ of Fig. 1, and Fig. 3 is a sectional plan view of the same on the lines $y y$ of Fig. 1.

35 The pair of curtains A A are supported in the usual manner from the upper end of the window-frame B, provided with the sill C, carrying on top, near each side, a bearing, D, in which is pivoted an arm, E, provided at its 40 free end with a threaded pin, F, extending outwardly at right angles to the arm E and passing through the curtain near its inner edge. On the pin F, at the rear of the curtain, is held a washer, G, and a concave 45 washer, H, is held in the front of the curtain on the said pin F. A handle, I, screws on the threaded pin F against the face of the washer H, so that the two washers G and H firmly

clamp the curtain and hold it in place on the pin F.

At the pivoted end of the arm E is formed a lug, J, standing nearly at right angles to the arm E, so that when the latter is swung upward past the vertical position, as shown to the left in Fig. 1, the said lug then rests 50 on the sill C and prevents a further sidewise swinging motion of the arm E. When the curtain is hung on the window-frame B, then the pin F is passed through the curtain near its inner edge, the arm E then being in a 55 horizontal position resting on the window-sill C, as shown to the right in Figs. 1 and 3. The washer H is then placed on the pin F in front of the curtain and pressed against the rear washer, G, by the handle I, screwing 60 65 on the pin F, the washer G having been placed on the pin F before the latter was passed onto the curtain. When the operator desires to lift and fold the curtain to one side, he takes hold of the handle I and swings the 70 arm E upward into the position shown to the left in Fig. 1, the lug J then resting on the window-sill C and preventing a further swinging motion of the arm. The latter in its upward movement carries with it part of the 75 curtain, so that the latter is folded to one side of the window-frame, as shown to the left in Fig. 1, and held there for the reason that the arm E has passed the vertical line.

When the operator desires to have the curtain closed, he swings the arms E into a horizontal position, as shown to the right in Fig. 1, the said arms then resting on the window-sill.

It will be seen that by the improved de- 85 vice the curtains can be quickly and symmetrically lifted and folded to one side of the window-frame or held in a closed position whenever desired.

Having thus fully described our invention, 90 we claim as new and desire to secure by Letters Patent—

1. In a curtain - holder, the combination, with an arm pivoted on the window-frame, of a pin formed on the free end of the said 95 arm and engaging the curtain, and a handle

held on the said pin for conveniently operating the arm, substantially as shown and described.

2. In a curtain - holder, the combination, 5 with an arm pivoted on the window - frame and provided at its pivoted end with a lug and on its free end with a threaded pin, of washers held on the said pin to clamp the

curtain, and a handle screwing on the said pin to press the washers onto the curtain, substantially as shown and described.

DAVID D. NOLLEY.
ROBERT L. WYATT.
